Park Ridge, Ill., assignors to Multi-Sort Systems Incorporated, Chicago, Ill., a corporation of Illinois

Application February 14, 1946, Serial No. 126,559

Term of patent 14 years

(Cl. D64—11)

To all whom it may concern:

Be it known that we, Hunter E. Hooe and Thomas O. Mehan, citizens of the United States, residing at Chicago and Park Ridge, respectively, in the county of Cook and State of Illinois, have jointly invented a new, original, and ornamental Design for a Card Punching Machine, of which the following is a specification, reference being had to the accompanying drawing, forming a part thereof.

Fig. 1 is a front perspective view of a card punching machine showing our new design, the side not shown, and the back thereof being plain; and Fig. 2 is a side elevational view thereof.

We claim:

The ornamental design for a card punching machine, as shown and described.
